UNITED STATES PATENT OFFICE.

LOUIS H. BIEN, OF PALO ALTO, CALIFORNIA.

PROCESSING AND DEHYDRATING APPARATUS.

Application filed November 4, 1926. Serial No. 146,085.

This invention relates to an apparatus whereby fruits, vegetables and other products may be processed and dehydrated by the action of humid air, heat and dehydration.

The object of the present invention is to generally improve and simplify the construction and operation of a device of the character described; to provide an apparatus in which blowers, fans or other air circulating and reversing mechanisms may be entirely eliminated by moving the product to be treated at a sufficient velocity to create air circulation and by intermittently reversing the movement and further and more specifically to provide a rotating support for the product to be treated, with means for automatically reversing a crate at predetermined time intervals.

One form which the invention may assume is shown by way of illustration in the accompanying drawings in which:—

Figure 1 is a plan view of the apparatus, said view being partly broken away and shown in section to disclose the interior construction,

Figure 2 is a central vertical cross section taken on the line II—II of Figure 1.

Referring to the drawings, in detail, A indicates a substantially cylindrical-shaped housing supported by concrete or other suitable foundation, generally indicated at B. The housing is covered by a roof section C and this is provided with a stack 2, the function of which will hereinafter be described.

Referring to Figure 2, it will be noted that the roof section is extended a considerable distance beyond the cylinder wall A and that a second wall 3 is employed. This wall forms an annular passage through which warm air is delivered to the interior of the housing. Mounted on a shelf or platform 4 are a plurality of heaters 5. Any suitable type of heater may be employed such as ordinary coal-oil heaters, gas heaters or the like. The heat produced naturally tends to rise and is prevented from escape by the overhanging roof section C. The heat

enters an annular passage 6 formed between the wall sections A and 3 and passes downwardly through this passage and enters the lower portion of the processing or dehydrating chamber D through a substantially annular inlet opening 7, over which is placed a baffle plate 8.

Formed centrally of the chamber D is a pit E and covering the pit is a turn-table 9. This turn-table is provided with stack sections indicated at 10 and 11 and trucks 12 are adapted to be received thereby, the trucks serving the function of entering the product to be treated and removing the same and also that of supporting the product while it is being treated. The turn-table is supported at its outer end by means of anti-friction bearings, such as indicated at 14 and it is rotated through means of a central shaft 15, a reduction worm gear drive 16 and an electric motor 17. A reversing switch 18 is connected with the motor and a handle 19 connected therewith automatically throws the switch from one position to another, when the device is in operation. The actuating mechanism or lever 19 of the reversing switch is so controlled that the turn-table will, for instance, rotate a given number of revolutions in one direction and will then be reversed and rotated a similar number of revolutions in the opposite direction, this being automatically continued until treatment of the product has been completed.

For the purpose of permitting ready insertion and removal of the product to be treated, one side of the housing is extended and indicated at F. Doors G are provided at this point to open and close the chamber D, and trucks 10^a extend into the housing so that the track sections 10 and 11 may align therewith when the product is to be inserted or removed. A simple method of handling a product is thus provided, as the product can be loaded on trucks exterior of the housing and are easily run into or out of the housing on the tracks provided.

One or more peek-hole openings such as indicated at 20 may be employed to observe standard forms of thermometer such as indicated at 21 and the heat within the chamber D will be observed by the operator from time to time. In order to maintain the temperature as desired a thermostat 22 may be employed. This is connected with a damper 23 and a stack and automatically opens and closes the same and thus maintains the desired temperature. The humidity of the atmosphere in the chamber D may also be controlled by inserting water pans 24.

In actual operation the trucks 12 are loaded with a product to be treated and they run along the tracks 10^a after opening the doors G and are finally delivered to the

turn-table 9. Two or more trucks may be placed thereon depending upon the size of the table. The product will then be placed in trays on top of the trucks and the trays 5 are preferably interspaced as shown in Figure 2 to permit a free circulation of air. After the heaters are started and the warm 10 air is delivered to the chamber D, the motor 17 is started and the turn-table rotated first a given number of revolutions in one direction and then it is automatically reversed and rotated in the opposite direction. This intermittent rotation and reverse is alternately repeated until the treatment of 15 the product is completed. The speed of rotation should be such that the atmosphere circulates freely between the trays and the product is thus heated or processed and also dehydrated.

20 The temperature employed is regulated by the thermostat 22 and the humidity content may be regulated by inserting a greater or smaller number of evaporating pans such as indicated at 24. It should be understood 25 that a fairly high humidity is desired, as this has been found more efficient both for processing and dehydrating purposes. A uniform product is obtained, for instance, when dehydrating, as the reversal of the rotating support causes the air to circulate 30 between the trays first in one direction and then in another. This air is, of course, also circulating upwardly through the chamber and as it is delivered at a point just below 35 the trucks, the heat is uniformly and efficiently applied.

The apparatus is exceedingly simple and substantial in construction and will take care of practically any capacity required as it 40 is merely necessary to increase the diameter of the housing to permit increase in capacity.

While certain features of the present invention are more or less specifically described, I wish it understood that various 45 changes may be resorted to within the scope of the appended claims. Similarly that the materials and finishes of the several parts employed may be such as the manufacturer may decide or varying conditions or uses 50 may demand.

Having thus described my invention, what I claim and desire to secure by Letters Patent is:—

1. An apparatus of the character described, comprising a substantially cylindrical-shaped vertically disposed wall, a roof section, supported thereby and extending a considerable distance over the vertical wall, a second vertical wall interspaced with relation to the first wall and forming an air inlet passage, a plurality of heaters supported with relation to the upper end of said inlet passage, said heaters being covered by the roof section and said roof sections slant-

ing to direct heat into the upper end of the 65 passage, means for directing air from the lower end of said passage into the housing, a stack connected with the roof and forming an outlet for the heated air, means in the stack for maintaining a predetermined temperature within the housing. 70

2. An apparatus of the character described, comprising a substantially cylindrical-shaped vertically disposed wall, a roof section supported thereby and extending 75 a considerable distance over the vertical wall, a second vertical wall interspaced with relation to the first wall and forming an air inlet passage, a plurality of heaters supported with relation to the upper end of said 80 inlet passage, said heaters being covered by the roof section and said roof sections slanting to direct heat into the upper end of the passage, means for directing air from the lower end of said passage into the housing, a stack connected with the roof and forming 85 an outlet for the heated air, means in the stack for maintaining a predetermined temperature within the housing, means for regulating the humidity of the air entering the 90 housing and a rotatable support within the housing to receive and support products to be treated.

3. An apparatus of the character described comprising a vertically arranged wall forming an enclosure, a roof section supported by said wall and overhanging the same, a second vertical wall arranged exteriorly of the first-named wall and spaced therefrom, said second vertical wall being disposed beneath the overhanging roof and extending short thereof forming an air inlet 95 passage, heating means adapted to deliver heated air between the walls, said first vertical wall having openings adjacent the bottom thereof whereby heated air may pass within the enclosure, said enclosure being formed with an outlet at its top to permit the escape for the heated air. 100

4. An apparatus of the character described comprising a vertically arranged wall forming an enclosure, a roof section supported by said wall and overhanging the same, a second vertical wall arranged exteriorly of the first-named wall and spaced therefrom, said second vertical wall being disposed beneath the overhanging roof and extending short thereof forming an air inlet 105 passage, heating means adapted to deliver heated air between the walls, said first vertical wall having openings adjacent the bottom thereof whereby heated air may pass within the enclosure, said enclosure being formed with an outlet at its top to permit the escape for the heated air, a rotatable support within said enclosure to receive and support products to be treated. 110
